HYDRAULIC DIAPHRAGM

Robert R. Crookston, Houston, Tex., assignor, by
mesne assignments, to Standard Oil Develop-
ment Company, Elizabeth, N. J., a corporation
of Delaware

Application May 14, 1951, Serial No. 226,205

8 Claims. (Cl. 137—793)

1

The present invention relates to flexible diaphragms which are suitable for exposing to fluid pressure. More particularly, the invention is directed to a hydraulic diaphragm which has outstanding life characteristics under flexing.

The present invention may be briefly described as a circular diaphragm comprising a deformable base member defining a U-shaped fold and having at least a layer of woven fiber ribbons superimposed thereon and molded to said base member. Each of the ribbons except a bottom ribbon overlaps a lower ribbon. The ribbons in the layer extend at least across the U-shaped fold of the diaphragm.

The ribbons in the diaphragm of the present invention may extend across a chord of the circular diaphragm to intersect the U-shaped fold or they may be caused to extend radially across the U-shaped fold of the diaphragm, particularly when the diaphragm defines a concentric circular opening. The invention will be better understood by reference to the drawing in which

Fig. 1 is a view looking downward on a diaphragm showing the superimposition of the woven fiber ribbons on the base member;

Fig. 2 is a view of the diaphragm of the present invention embodying an annular U-shaped fold;

Fig. 3 is a view taken along the lines III—III of Fig. 2;

Fig. 4 is a view similar to that of Fig. 2 showing a diaphragm of the present invention defining a concentric circular opening;

Fig. 5 is a cross-sectional view of apparatus illustrating the use of diaphragms identical to those of Figs. 2 and 4; and

Fig. 6 shows an arrangement of the interlacing of a plurality of layers of the diaphragm of the present invention.

Referring now to the drawing and particularly to Fig. 1, numeral 11 designates a deformable base member which may be constructed of synthetic rubber, such as one of the Hycar type. Arranged on the base member is a first ribbon 12 of a woven fibrous material, such as woven nylon, cotton, or the like. Ribbon 12 extends across the base member 11. Overlapping the ribbon 12 is a second ribbon 13 of the same material which similarly extends across the base member 11. Similarly, overlapping ribbon 13 is a third ribbon 14 which also extends across the base member 11. Ribbons 15, 16, 17, 18, 19, and 20 are arranged similar to the previously described ribbons and it will be noted that each succeeding ribbon overlaps the preceding ribbon. It will

2

be noted further that all of the ribbons overlap in an area 21 concentric with the periphery of the base member 11. The overlapping area 21 assumes roughly a conical shape as shown more clearly in Fig. 3. It is desirable that in each individual layer the lap at the edges is about 50%; that is, at least two thicknesses of woven ribbon exist at any spot. The layer of ribbons is molded to the base member 11.

In the view of the present invention of Fig. 2 it will be noted that the deformable base member 11 defines a U-shaped annular fold 25 and a circular concentric area 26 of greater thickness than the remaining area of member 11. The circular concentric area 26 is on a side opposite from that of the layer of ribbons 27 and results from the overlapping of the ribbons at one point 21 shown in Fig. 1. In order to have the diaphragm function properly, it is necessary to compensate for the overlapping of the ribbons as shown in Figs. 1 and 2. While the circular concentric area 26 is illustrated as a substantially flat raised portion, it may be substantially conical in shape to correspond with the overlapping area 21 of the ribbons.

Referring now to Fig. 3, it will be seen that the base member 11 is provided with at least a layer of ribbons 27 on the side opposite the area 26. The layer 27 is arranged on the side not exposed to fluid pressure.

Referring now to Fig. 4, a base member 30 which has ribbons arranged radially thereto defines a concentric opening 31. The base member 30 also defines an annular U-shaped member 32. Like the diaphragm of Figs. 1 to 3, a plurality of ribbons extend across the base member 30. These ribbons beginning with ribbon 33 overlap each other in a fashion similar to those in Figs. 1 to 3; thus, ribbon 34 overlaps ribbon 33 and ribbon 35 overlaps ribbon 34. In a similar fashion ribbons 36, 37, 38, 39, 40, 41, 42, 43, 44, 45, 46, 47, 48, 49, 50, 51, 52, 53, 54, 55, and 56 each overlap the preceding ribbon, insuring a layer wherein the ribbons are of at least two thicknesses.

Referring now to Fig. 5, a housing member 60 provided with a cover plate 61 is secured by bolts 62. Arranged in the housing 60 is a first plate 63 to which is connected a second plate 64. The housing defines a first cavity 65 in which the plate 63 is arranged. The housing also defines a second cavity 66 in which the plate 64 is located, the two plates being interconnected by threaded bolts 67. A first diaphragm 70, in accordance with the present invention, provided with a layer of over-

lapping ribbons 71 is arranged in the housing 60 between the plate 64 and a cover plate 72 which defines an inlet 73. The diaphragm 70 is arranged in the cavity 65 and is locked securely in place between a shoulder 74 of the housing 60 and a shoulder 75 of the cover plate 72. This cover plate 72 may be securely bolted to the housing 60 by threaded bolts 76.

A second diaphragm 80 is arranged in the cavity 65. This diaphragm has a concentric opening 81 similar to openings 31 of the diaphragm 30.

The diaphragm 80 is arranged between shoulder 82 of plate 61 and shoulder 83 of the housing 60. The diaphragm 80 is also secured to the plate 63 by a locking plate 84 which is secured to plates 63 and 64 by threaded bolts 67. The cover plate 61 defines a port 85 communicating with a source of fluid pressure. The device may suitably be connected to a pressure indicating mechanism. For example, pin 90 which is sealed against pressure by O-ring 91 may be used to operate an indicating or actuating means not shown.

Referring to Fig. 6, it will be seen that the base member 11 is provided with overlapping ribbons which may be designated respectively as 90, 91, and 92 comprising a bottom layer. Overlapping this bottom layer is a second layer comprised of ribbons 93, 94, 95, and 96 while a top layer of ribbons 97, 98, and 99 is arranged on the middle layer. Thus, in accordance with the present invention, it may be desirable to provide a plurality of layers of woven fiber ribbons to secure the benefits of the invention.

The present invention may be employed for indicating pressure and in other uses to which a hydraulic diaphragm may be employed, such as for actuating brakes and pumps and in various other numerous requirements to which diaphragms may be put, such as devices controlled by fluid pressure.

The device of Fig. 5 shows the use of two diaphragms 70 and 80, each of which defines, respectively, an annular U-shaped fold 77 and 87 and each of which has a layer of ribbons such as 71 and 88. Fluid pressure may be exerted against the diaphragm 70 through inlet 73 which, in turn, will cause lifting of the plate 64 and the plate 63. A greater pressure than that exerted against diaphragm 70 may be exerted against the diaphragm 80 through port 85 which, in turn, will serve to oppose the upward movement of the plates 63 and 64. A small pressure change in the fluid exerted against either of the diaphragms will thus cause a movement thereof. The plate 67 may be connected to a suitable actuating or indicating means (not shown) by pin 90, which moves in response to movement of plate 67. The U-shaped folds 77 and 87 of diaphragms 70 and 80 are thus exposed to stress. By virtue of employing at least a layer of woven fiber ribbons extending at least across the U-shaped folds, it is possible to reinforce them to the extent of providing a diaphragm of increased resistance toward destruction by the constant flexing that the U-shaped fold thereof undergoes. For example, a diaphragm in accordance with the present invention has been subjected to 90,000 repetitions of 0-500 p. s. i. impact cycles with $\frac{1}{4}$ " stroke without failure. Another diaphragm has been subjected to almost 100,000 cycles from 0 to 1000 p. s. i. with impact at short stroke without destruction.

The woven fiber making up the ribbons of the diaphragm of the present invention may be constructed of either synthetic or natural fibers.

Nylon is an excellent synthetic fiber for use in the diaphragm of the present invention. Cotton and other naturally occurring fibers such as linen, silk, ramie, and the like, may be employed. Other synthetic fibers, such as rayon, and the like may also be used in the ribbons employed in the practice of the present invention.

In the specification and claims where the term "ribbon" has been employed, ribbon is used in the sense as defined in Webster's New International Dictionary, second edition, unabridged (1936), and in the sense it is used in the textile industry; for example, Carmichael, Linton and Price, Callaway Textile Dictionary, first edition, Callaway Mills, La Grange, Georgia, 1947, define ribbon as follows: "Ribbon: a fillet or narrow woven fabric of varying widths—commonly $\frac{1}{4}$ to 3 inches—having selvage edges, principally of rayon, silk or velvet and used for trimmings, decorations, etc."

The deformable base member may be constructed of natural or synthetic rubber depending on the fluid to which it is exposed. Rubbers of the general Hycar type may suitably be used. Other synthetic rubbers which may be employed include Buna, Butyl, and the like, which do not acquire a permanent set.

The nature and objects of the present invention having been completely described and illustrated, what I wish to claim as new and useful and to secure by Letters Patent is:

1. A diaphragm comprising a deformable base member defining a substantially U-shaped fold having at least one layer of woven fiber ribbons superimposed thereon and molded to said base member comprising at least two thicknesses of ribbons extending across and substantially covering said base member, each of said ribbons, except a bottom ribbon, overlapping a lower ribbon, said ribbons extending at least across the U-shaped fold of said diaphragm.

2. A circular diaphragm comprising a deformable base member defining a substantially U-shaped annular fold adjacent its periphery having at least one layer of woven fiber ribbons superimposed thereon and molded to said base member comprising at least two thicknesses of ribbons extending across and substantially covering said base member, each of said ribbons, except a bottom ribbon, overlapping a lower ribbon, said ribbons extending at least across the U-shaped fold of said diaphragm.

3. A circular diaphragm comprising a deformable base member defining a substantially U-shaped annular fold adjacent its periphery having at least one layer of woven fiber ribbons superimposed thereon and molded to said base member comprising at least two thicknesses of ribbons extending across and substantially covering said base member, each of said ribbons, except a bottom ribbon, overlapping a lower ribbon, said ribbons extending at least across a chord of said diaphragm and intersecting said U-shaped fold.

4. A circular diaphragm comprising a deformable base member defining a substantially U-shaped annular fold adjacent its periphery having at least one layer of woven fiber ribbons superimposed thereon and molded to said base member comprising at least two thicknesses of ribbons extending across and substantially covering said base member, each of said ribbons, except a bottom ribbon, overlapping a lower ribbon, said ribbons extending at least across an outer side of the fold, said diaphragm defining a con-

centric area of greater thickness than a remaining area thereof corresponding generally to a point where all of said ribbons overlap.

5. A circular diaphragm comprising a deformable base member defining a substantially U-shaped annular fold adjacent its periphery having at least one layer of woven nylon ribbons superimposed thereon and molded to said base member comprising at least two thicknesses of ribbons extending across and substantially covering said base member, each of said ribbons, except a bottom ribbon, overlapping a lower ribbon, said ribbons extending at least across the U-shaped fold of said diaphragm.

6. A circular diaphragm comprising a deformable base member defining a substantially U-shaped annular fold adjacent its periphery having at least one layer of woven silk ribbons superimposed thereon and molded to said base member comprising at least two thicknesses of ribbons extending across and substantially covering said base member, each of said ribbons, except a bottom ribbon, overlapping a lower ribbon, said ribbons extending at least across the U-shaped fold of said diaphragm.

7. A circular diaphragm comprising a deformable base member defining a substantially U-shaped annular fold adjacent its periphery having at least one layer of woven nylon ribbons superimposed thereon and molded to said base member comprising at least two thicknesses of

ribbons extending across and substantially covering said base member, each of said ribbons, except a bottom ribbon, overlapping a lower ribbon, said ribbons extending at least across an outer side of the fold, said diaphragm defining a concentric area of greater thickness than a remaining area thereof corresponding generally to a point where all of said ribbons overlap.

8. A circular diaphragm comprising a deformable base defining a substantially U-shaped annular fold adjacent its periphery having at least one layer of woven silk ribbons superimposed thereon and molded to said base member comprising at least two thicknesses of ribbons extending across and substantially covering said base member, each of said ribbons, except a bottom ribbon, overlapping a lower ribbon, said ribbons extending at least across an outer side of the fold, said diaphragm defining a concentric area of greater thickness than a remaining area thereof corresponding generally to a point where all of said ribbons overlap.
